UNITED STATES PATENT OFFICE.

WILLIAM RICHARD GREEN, OF WESTMINSTER, ENGLAND.

DESIGN FOR CORKS OR STOPPERS OF BOTTLES.

Specification forming part of Design No. 6,321, dated December 24, 1872.

To all whom it may concern:

Be it known that I, WILLIAM RICHARD GREEN, of No. 40 Strand, in the city of Westminster, England, perfumer, have invented and produced a new and original Design for Corks or Stoppers of Bottles and Vials, of which the following is a specification:

The nature of my design is fully represented in the accompanying drawing, to which reference is made.

I claim as my invention—

The design for corks or stoppers for vials and bottles, as shown, namely, making them in the shape of a crown, without regard to the material of which they are manufactured.

Dated this 9th day of October, 1872.

WILLIAM RICHARD GREEN.
